[57] CLAIM

The ornamental design for a fabric display rack, as shown and described.

DESCRIPTION

FIG. 1 is a front perspective view of a fabric display rack embodying our new design;

FIG. 2 is a side elevational view taken from the left of FIG. 1, the side opposite being identical;

FIG. 3 is a rear elevational view thereof; and

FIG. 4 is a top plan view thereof.

The bottom of the fabric display rack is plain and unornamented.
